UNITED STATES PATENT OFFICE.

KRAFT BOOTH, OF CHICAGO, ILLINOIS.

SOLDERING-IRON.

SPECIFICATION forming part of Letters Patent No. 664,310, dated December 18, 1900.

Application filed October 20, 1898. Serial No. 694,064. (No model.)

To all whom it may concern:

Be it known that I, KRAFT BOOTH, a citizen of the United States, residing at Chicago, in the county of Cook and State of Illinois, have 5 invented a certain new and useful Improvement in Soldering-Irons, of which the following is a specification.

My invention relates to soldering-irons, and has for its object to provide a new and improved soldering-iron of which the following is a description, reference being had to the accompanying drawings, wherein—

Figure 1 is a view of a soldering-iron embodying my invention. Fig. 2 is a longitudinal section through Fig. 1. Fig. 3 is a section on line 3 3, Fig. 2.

Like letters refer to like parts throughout the several figures.

In the accompanying drawings I have shown 20 an iron embodying my invention constructed so as to be self-heating, as it were. In this construction the soldering-iron proper, A, is made of copper in the usual manner and is formed of a solid piece. This part A is attached to the shell B, which contains the combustion-chamber B', the part A projecting into said combustion-chamber. It is of course 25 evident that the part A may be connected with the shell B in any desired manner. As 30 herein illustrated, the shell B is provided at its lower end with an opening through which the part A is received, the shell being also provided with a series of projections or engaging pieces B², which also engage the part 35 A. It will therefore be seen that the part A has two sets of bearings in different planes, and hence its rigidity is insured. The part A is preferably made so as to snugly fit in the opening at the end of the shell B and be- 40 tween the engaging faces B². The shell B is preferably made of cast-iron, and hence when the parts are heated the copper expands in a greater degree than the iron, thus making a firm contact at the engaging surfaces. This 45 expansion of the copper binds it firmly in position while the iron is being used. The combustion-chamber B' is connected by means of a suitable opening B³, preferably through the handle B⁴ of the iron, with a 50 source of gas-supply. I prefer to have this combustion-chamber connected both with a source of gas-supply and a source of air-sup-

ply, as shown—for example, by means of the two tubes or pipes B⁵ B⁶—so that air is combined with the gas. These tubes or pipes 55 are preferably elastic, so that the iron may be moved about from place to place without injuring the connections. The combustion-chamber B' is provided with one or more suitable openings B⁸, by which the gas con- 60 tained therein is ignited. When the gas is thus ignited, it burns in the combustion-chamber B', the combustion entirely surrounding the outer periphery of the part A contained within said chamber. I have found 65 that by this construction I am able to get a much more efficient soldering-iron and still use less gas than has been heretofore possible. In this construction the burning of the gas is comparatively noiseless. I also find 70 that this iron can be made very cheaply on account of the small amount of copper used. When the iron cools, the copper contracts and can be easily removed for pointing or for other purposes. It will thus be seen that the 75 only part of the iron—namely, the part A—which can wear out is easily detached from the rest of the iron and can be replaced at will. The shell B, if made of cast-iron, for example, has no tendency to wear out and 80 can be indefinitely supplied with new pieces of copper, thus making the use of this soldering-iron exceedingly economical.

I have shown a certain construction for purposes of illustration; but it is of course evident that the construction may be varied without departing from the spirit of my invention, and I therefore do not wish to be limited to the construction shown.

I claim—

1. A soldering-iron, comprising a soldering-head and holding device for the same, a shell-like portion of said holder surrounding the inner end of the head and opening in direction opposite to that of the point of the head, 95 the head smaller in cross-section than the shell-like portion and thus projecting free from the walls of the shell-like portion into the same; a combustion-chamber connected with and forming part of said shell-opening 100 and surrounding the projecting head, a handle and discharge-way leading to the combustion-chamber; substantially as shown and described.

2. A soldering-iron, comprising a soldering-head and holding device for the same, a shell-like portion of said holder surrounding the inner end of the head and opening in direction opposite to that of the point of the head, a combustion-chamber connected with and forming part of said shell-opening, a handle and discharge-way leading to the combustion-chamber, an apron about and overhanging the rearward openings from the shell, so that the gases for combustion are directed back against the apron and then forward so as neither to overheat the hand nor crack the glass which is being worked upon, while at the same time heating the head by surrounding the same; substantially as shown and described.

3. A soldering-iron, comprising a soldering-head, a shell containing a combustion-chamber and provided with an opening through which said soldering-head is received so as to project partly into the combustion-chamber, a series of bearing-points within the combustion-chamber and connected with the walls thereof, said soldering-head of such size as to slip readily into position, the soldering-head formed of material which expands more readily under the influence of heat than the material of which the shell is made, whereby when heat is applied thereto the soldering-head expands so as to be held firmly in position.

4. A soldering-iron, comprising a soldering-head, a hollow shell containing a combustion-chamber, an opening in said shell through which the end of the soldering-head is re-

ceived, a series of projections extending from the inner wall of said combustion-chamber and adapted to engage the said soldering-head between its inner end and the opening in the shell and hold said soldering-head in position.

5. A soldering-iron, comprising a soldering-head, a shell provided with a combustion-chamber, an opening in said shell through which the soldering-head passes, so that a portion of said soldering-head extends into the combustion-chamber the outer end of said chamber being closed when the soldering-head is in position, said soldering-head engaging the shell at two points separated by a space forming part of the combustion-chamber, an igniting-opening connecting said combustion-chamber with the outer air, a handle connected with said shell, a passage-way through said handle connecting with the combustion-chamber, and means for connecting said passage-way with a source of gas-supply.

6. A soldering-iron, comprising a soldering-head, a shell hollowed so as to form a combustion-chamber, an opening in the outer end of said shell smaller in cross-sectional area than the chamber and adapted to be closed by the insertion of the soldering-head, one or more projecting parts integral with said shell and projecting into said chamber, said projecting part or parts engaging the soldering-head so as to hold it in position.
